(57) **CLAIM**

The ornamental design for a dental floss container for a dental brush, as shown and described.

DESCRIPTION

FIG. 1 is a perspective view of a dental floss container for a dental brush showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof; and,

FIG. 7 is a right side elevational view.

The broken lines in the drawing are for illustrative purposes only and form no part of the claimed design.
